UNITED STATES PATENT OFFICE

CLARENCE SPEER, OF SAN FRANCISCO, CALIFORNIA

SNOWPLOW

Application filed July 29, 1929. Serial No. 381,866.

My invention relates to improvements in snow plows for removing snow from roadways and the like wherein an elevating conveyor is mounted upon a carriage with its 5 lower end movable along the ground to pick up snow and carry the same to a delivery conveyor movable to deliver said snow rearwardly or to either side of the carriage.

The primary object is to provide an improved snow plow for road use.

Another object is to provide an improved snow plow operable to clear a wide path and to deliver snow rearwardly or to either side of the roadway as desired.

15 A further object is to provide an improved machine of the character described wherein an elevating conveyor movable in advance of a carriage for elevating snow from the ground is pivotally movable upon vertical 20 and horizontal axes to permit steering along a desired course and to conform to irregularities in the surface of ground to be cleared.

Another object is to provide an improved device wherein snow is elevated into a hopper 25 and delivered therefrom by a delivery conveyor movable to rearwardly or laterally extending positions.

A further object is to provide an improved machine provided with conveying means of 30 improved construction and arrangement to facilitate the removal of snow from roadways and the like.

A still further object is to provide an improved machine of the character described 35 having power means for actuating the several mechanisms and for propelling the machine along the ground, and which is self contained and efficient in operation.

I accomplish these and other objects by 40 means of the improved device disclosed in the drawings forming a part of the present application wherein like characters of reference are used to designate similar parts throughout the specification and drawings, 45 and in which—

Fig. 1 is a broken plan view of my improved snow plow;

Fig. 2 is a side elevation, parts being 50 broken away and shown in longitudinal vertical section;

Fig. 3 is a broken transverse vertical sectional detail of the hopper, and disclosing the driving connections to the delivery conveyor, the figure being drawn upon a larger scale;

Fig. 4 is a rear end elevation of the machine, the delivery conveyor being turned to deliver snow laterally from one side of the machine; and

Fig. 5 is a broken transverse vertical section disclosing the mounting and driving connections for the front elevating conveyor.

Referring to the drawings, the numeral 1 is used to designate in general a carriage 65 preferably comprising a wheel supported frame of suitable size and construction. An elevating conveyor designated in general by the numeral 2 is mounted upon the forward end of the carriage 1 by means of a yoke 3 having upwardly extending arms 4. The yoke 3 is pivotally movable relative to the carriage 1 upon a vertical axis, as at 6, and an upper driving shaft 7 is rotatably mounted upon the upper ends of the arms 4.

The conveyor 2 comprises a plurality of 75 endless conveyor members mounted over sprockets 8 secured upon the shaft 7, each member being provided with a plurality of conveyor buckets 9 secured thereon. The outer ends of the buckets 9 upon the outer 80 conveyor members are formed to project outwardly in overhanging relation to the edges. Spikes 11 are mounted in rows upon the conveyor members to project outwardly at substantially right angles to the surface of 85 said members between the buckets 9 of each member. The conveyor member 2 extends around sprockets 12 secured upon a lower shaft 13 mounted through the ends of arms 14 pivotally mounted at their upper ends 90 upon the shaft 7. Rollers 16 are mounted upon the shaft 13, preferably between adjacent conveyor members to support the lower ends of conveyors upon the ground.

The conveyor 2 inclines from the ground 95 in front of the carriage to a point above the body of the carriage. A hopper 17 is mounted upon the body of the carriage below the upper end of the conveyor 2. The hopper 17 is rotatably supported upon the car-

riage 1 by means of rollers 18 engaged within an annular channel guide 19 secured to the frame of the carriage. The upper end of the hopper is provided with a flaring flange 21.

A delivery conveyor designated in general by the numeral 22 is mounted above the rearward portion of the carriage 1. The conveyor 22 preferably consists of a pair of endless conveyor members mounted over sprockets 23 and 24 secured upon lower shafts 26 and an upper shaft 27 respectively, said conveyor members being provided with suitable conveyor buckets 28. The lower shafts 26 are mounted within the hopper 17. The upper shaft 27 is mounted upon the upper ends of arms 29 having their lower ends engaging the shafts 26. A brace 30 is secured to the hopper 17 and extended into engagement with a stay rod 31 extending between the arms 28 to support the conveyor in a slightly inclined position. The conveyor 22 is movable through an opening 32 formed in the flanged side of the hopper 17 and is movable with said hopper when the same is rotated upon the rollers 18.

The plow is operated by means of a suitable source of power such as an internal combustion engine 33 mounted upon the carriage, preferably upon the rearward portion of the carriage frame. Power is directed from the engine 33 through a suitable clutch 34 to a shaft 36 from which power is transmitted to a main drive shaft 37 through suitable transmission gears 38. Power from the main shaft 37 is delivered through a suitable differential to the rear wheels of the carriage 1 in the ordinary manner for propelling the carriage along the ground.

The elevating conveyor 2 is driven by suitable sprocket chains 39 operating over sprockets 40 secured upon the shaft 7 and sprockets 41 secured upon a driving shaft 42 having a pinion 43 meshing with a bevel gear 44 upon a shaft 45 driven by a similar gear and pinion 46 and 47 actuated by a suitable driving connection 48 connected to the main shaft 37 through a suitable clutch 49.

The delivery conveyor 22 is driven by means of a bevel gear 51 secured upon the driving connection 48 and meshing with a gear 52 secured upon a hollow shaft 53 extending upwardly through the center of the hopper 17. Oppositely faced bevel gears 54 and 55 are secured upon the shaft 53 and meshing with gears 56 and 57 respectively secured upon the shafts 26. The inner ends of the shafts 26 are supported by a collar 58 mounted upon a reduced portion of the shaft 53. The gears 55 and 57 are made sufficiently larger than the gears 54 and 56 to clear the latter, both of said sets of gears operating simultaneously to drive the conveyor members associated therewith in the same direction and at the same speed.

The hopper 17 is provided with an an-

nular gear ring 61 engaged by a pinion 62 secured upon a shaft 63 provided with oppositely facing bevel pinions 64 rotatably mounted thereon. A bevel gear 65 is secured upon the shaft 36 in meshing relation with both of the pinions 64 to drive the same simultaneously in opposite directions. A suitable clutch member 66 is feathered upon the shaft 63 and adapted to be moved from a normal neutral position permitting free rotation of both pinions 64 to operative positions locking either of said pinions to the shaft 63 whereby the pinion 62 and ring gear 61 may be actuated to turn the hopper 17 and the delivery conveyor in either direction about a vertical axis through the center of the hopper.

A platform 67 is mounted upon supports 68 secured upon the frame of the carriage 1 and extending over the hopper 17 with suitable clearance between said hopper and the elevating conveyor 2. The supports rest upon a yoke 70 carried by the hopper 17 and rotatably movable relative to the platform and its supports 68. An operator's seat 69 is mounted upon the platform 67, a shield 71 being mounted between the platform and the delivery end of the elevating conveyor 2 to deflect snow delivered by said conveyor downwardly into the hopper. Control pedals 72, 73, and 74 are mounted upon the platform and connected to the clutch members 34, 49, and 66 by suitable connecting means 75, 76, and 77 respectively, whereby said clutches may be readily actuated and controlled by the operator.

A steering post 78 extends upwardly through the hollow shaft 53, said post being provided with a suitable steering wheel 79 at its upper end and with a worm gear 80 at its bottom. A gear 81 is mounted within a suitable housing 82 in meshing relation with the worm gear 80 to actuate a shaft 83 and steering arm 84 adapted to steer the carriage 1 by means of a suitable drag link 85 in the ordinary manner.

In operation, the carriage is propelled forwardly along a path from which snow is to be cleared with the elevating conveyor inclining downwardly to the front and with the rollers 16 resting upon the ground so that the buckets 9 will just clear the ground when the conveyor is in operation. When the clutch 49 is moved to deliver power from the main shaft 37 to the shaft 45, the conveyor is driven in the direction indicated by the arrow, thereby causing the buckets 9 to pick up snow from the ground and deliver the same over the top of the conveyor into the hopper 17. The spikes 11 loosen the snow as the carriage 1 and conveyor 2 are advanced along the path to be cleared, and the loosened snow is picked up across the full width of the conveyor to provide an adequate clearance upon the sides of the carriage.

As the snow is delivered into the hopper 17, the delivery conveyor 22, actuated simultaneously with the conveyor 2 through its driving connections to the shaft 45 as above described, operates to remove the snow from the hopper. The conveyor 22, being of less width than the conveyor 2, is actuated at a correspondingly greater speed so that the snow will be carried away from the hopper as fast as it is elevated by the conveyor 2. The hopper 17 and conveyor 22 are moved to a position to deliver the snow either rearwardly over the end of the carriage 1 to be received and removed by suitable trucks 86, or laterally over either side of the carriage, as desired. Thus, if the path to be cleared of snow is so located that the snow removed may be dumped along one side, the hopper 17 and conveyor 22 are turned to a position such as shown in Fig. 4 and in dotted lines in Figs. 1, 2, and 3. If the snow is to be removed, the conveyor is shifted to its rearwardly extending position, as shown in full lines in Figs. 1, 2, and 3, the pivotal mounting and actuating means by which the hopper and conveyor are turned, permitting said hopper and conveyor to be readily turned to deliver the snow in a desired direction.

As the elevating conveyor 2 is advanced along the path to be cleared, the rollers 16 cause the lower end of the conveyor to be moved to conform to irregularities in the surface being traversed, the entire conveyor being moved pivotally upon the horizontal shaft 7 as a pivot. In steering the carriage along its path, the resistance of the snow against the front of the conveyor 2 will normally hold said conveyor in its course directly in front of the carriage. When the forward wheels of the carriage are turned to right or left, the pivotal movement of the yoke 3 relative to the frame of the carriage 1 causes the direction of the propelling force to be shifted so that as the machine is further advanced the conveyor will be moved in an angular relation to the carriage and thereby shifted to the right or left as desired. After the conveyor has been shifted to the desired position, the forward wheels of the carriage are moved to straighten the machine to its desired course, and to direct the propelling force to the conveyor along said course. The width of the path cut by the conveyor is such as to afford ample clearance of manipulating the carriage in back of the conveyor 2 to shift said conveyor and steer the machine along a roadway to be cleared of snow.

While I have illustrated and described my improved snow plow only in what I now regard as its preferred embodiment, the specific details of construction and arrangement are of course subject to modification in numerous ways without departing from the spirit of my invention. I therefore do not

wish to restrict myself to the specific construction disclosed, but desire to avail myself of all modifications which may fall within the scope of the appended claims.

Having thus described my invention what I claim as new and desire to secure by Letters Patent is—

1. In a snow plow, a carriage, an elevating conveyor comprising a supporting yoke pivotally mounted upon the front of the carriage; an upper driving shaft mounted upon the yoke; arms pivotally mounted at one end thereof upon the driving shaft; a lower shaft mounted upon the opposite ends of the arms; endless conveying means mounted over the shafts and provided with elevating buckets; and rollers mounted upon the lower shaft and supporting the lower end of the conveyor upon the ground in advance of the carriage, the arms and conveying means swinging freely from the upper shaft to conform to irregularities in the surface of the ground.

2. In a snow plow, a carriage, an elevating conveyor comprising a supporting yoke mounted upon the front of the carriage; an upper driving shaft mounted upon the yoke; arms each pivotally mounted at one end thereof upon the driving shaft; a lower shaft mounted upon the opposite ends of the arms; a plurality of endless conveyor members mounted in spaced parallel relation over the shafts and actuated by the upper driving shaft and each provided with a plurality of conveyor buckets; and rollers mounted upon the lower shaft between adjacent conveyor members and supporting the lower end of the conveyor upon the ground in advance of the carriage.

3. In a snow plow, a carriage, an elevating conveyor comprising a supporting yoke mounted upon the front of the carriage; an upper driving shaft mounted upon the yoke; arms each pivotally mounted at one end thereof upon the driving shaft; a lower shaft mounted upon the opposite ends of the arms; a plurality of endless conveyor members mounted in spaced parallel relation over the shafts and actuated by the upper driving shaft and each provided with a plurality of conveyor buckets, the outer edges of the outer buckets being flared and extending outwardly past the outer arms; rollers mounted upon the lower shaft between the conveyor members and supporting the lower end of the conveyor upon the ground in advance of the carriage with the buckets clearing the surface of the ground, the arms and conveyor members swinging freely upon the upper shaft to conform to irregularities in the surface of the ground.

In witness whereof, I hereunto set my signature.
